UNITED STATES PATENT OFFICE.

HENRY H. LAMPERT, OF CHICAGO, ILLINOIS.

REINFORCING SYSTEM FOR CONCRETE

1,265,094.

Specification of Letters Patent.

Patented May 7, 1918.

Application filed December 26, 1917. Serial No. 208,966.

To all whom it may concern:

Be it known that I, HENRY H. LAMPERT, a citizen of the United States of America, and a resident of Chicago, county of Cook, 5 and State of Illinois, have invented certain new and useful Improvements in Reinforcing Systems for Concrete, of which the following is a specification.

The main objects of this invention are to 10 provide an improved reinforcing system for concrete embodying the use of a plurality of rods or bars spaced apart in rows; to provide improved means for spacing said rods; to provide improved means for supporting 15 said spacing means rigidly in place; to provide improved means for locking said supporting means and said spacing means together; to provide improved means for securing the reinforcing rods to said spacing 20 means; and to provide a system of reinforcing of this kind particularly adapted for use in the formation of beams, pillars, and the like.

An illustrative embodiment of this invention is shown in the accompanying drawings, 25 in which—

Figure 1 is a cross section of a mold for a beam, showing the improved system of reinforcing arranged therein.

30 Fig. 2 is a similar view showing a slight modification of the reinforcing system as regards the supporting of the first row of rods.

Fig. 3 is a transverse sectional detail 35 taken on the line 3—3 of Fig. 1.

Fig. 4 is a similar view taken on the line 4—4 of Fig. 2.

Fig. 5 is a perspective view of one of the 40 supporting members which supports the second spacing member above the first spacing member in the system shown in Fig. 1.

Fig. 6 is a similar view of the supporting members which support the first or lowermost spacing member in the system shown 45 in Fig. 2.

Fig. 7 is a perspective view of one of the supporting members used for supporting the spacing members on edge.

This improved system of reinforcing 50 involves the use of a plurality of spacing members 1 supported in spaced relation one above another by means of supporting members 3 so as to support rows of reinforcing rods or bars 2 thereon. Fastening 55 means and locking means are provided for

securing the rods in place on the spacing members and for locking the spacing members and the supporting members together.

The spacing members 1 are herein shown in the form of flat, comparatively thin, 60 metal strips which vary in width, depending upon the distance the rods are to be spaced apart. These strips are used either flat or on edge. When used edgewise, notches are formed in the upper edges in which the bars 65 2 are to be seated. The spacing of the notches along the strips serves to properly space the bars in their respective rows.

The supporting members by which the spacing strips 1 are held in spaced relation 70 are in the form of chairs 3 each comprising essentially a pair of depending legs 4 and 5 connected together at their upper ends and spaced apart at their lower ends. The exact form of these chairs depends somewhat 75 upon the place in the system in which they are to be used and the arrangement of the spacing members which they are to support.

When the first or lowermost spacing strip 80 is supported with its face substantially parallel to the adjacent wall of the mold, and the other strips above are disposed edge-wise to said first strip, the supporting members for said first strip are preferably of the 85 form shown in connection with said first strip in Fig. 1, and the supporting members for the strip next above are preferably of the form shown in Fig. 5. When the first or lowermost spacing strip is supported on 90 edge as regards the adjacent wall of the mold, the supporting members therefor are preferably of the form shown in Fig. 6. For supporting a spacing strip on edge above another which is also on edge, the supporting members are preferably of the form 95 shown in Fig. 7. In the form of supporting member shown in Fig. 1 for supporting the lowermost spacing strip, the legs 4 and 5 are substantially parallel, and their connection at their upper ends provides a transverse seat part upon which the spacing member 1 rests. The other forms of supporting members 3 herein shown are all of substantially an inverted V-shape construction. 100

In the form shown in Fig. 5, a notch or recess 6 extends inwardly from the upper end into which a spacing strip 1 is received. Lugs 7 are formed on the ends of the legs 4 and 5 which are adapted to extend through 110

recesses 8 formed in the strip 1 and then be bent over so as to rigidly secure the supporting member to the spacing strip upon which it rests. In the form shown in Fig. 6, a 5 notch or recess 6 extends inwardly from the upper end thereof into which the spacing member 1 is received, and the lower ends of the legs 4 and 5 rest directly upon the mold, as shown in Figs. 2 and 4. In the form 10 shown in Fig. 7, notches 6 extend inwardly from the upper end and other notches 9 extend upwardly from the bottoms of the legs 4 and 5. The notches 9 are adapted to permit this supporting member 3 to straddle a 15 spacing member 1 above which it is to support another spacing member, and said other spacing member is received in the notches 6.

Fastening means may be provided, if desired, for securing the reinforcing rods 2 20 to the respective spacing members 1, which may be accomplished in various ways, as illustrated in the drawings. When the lowermost spacing member 1 is disposed with the face substantially parallel with the adjacent 25 wall of the mold, the rods may be held in place by means of fingers 10 bent around the rods. These fingers may be formed either on the supporting member 3, which is the form herein shown and which is more fully 30 described and claimed in my copending application Serial No. 202,439, filed November 17, 1917, or they may be integrally formed on the spacing member itself, as shown and described in my copending application, Serial 35 No. 207,114, filed December 14, 1917. For the bars supported on the uppermost or outermost spacing member, the locking is conveniently accomplished by having pieces of wire 11 secured in apertures 12 formed in the 40 spacing member 1 adjacent to the points at which the bars are to be supported, which wires are adapted to be twisted around the bars as shown in the figures. In the modifications herein shown, the intermediate rows 45 of bars are retained in place through their being supported in the notches formed in the edges of the spacing members 1 and having the spacing members above placed in such close proximity to those below that the space 50 between the opposed edges of the spacing members is too narrow to permit displacement of the rods. The retention of the intermediate rods in their respective places may be enhanced by placing the chairs or supporting members 3 astride the rods as indicated in some parts of the figures.

The locking means for securing the spacing members 1 and the supporting members 3 rigidly together are most conveniently provided by having shoulders or lugs 13 upset from the plane of the strips or spacing members 1 and located so that when the strips rest in the bottoms of the notches 6, said lugs or shoulders engage the under 65 side of the upper end of the chairs.

In order to facilitate the flow of concrete in and around all parts of the supporting and spacing means for the rods, openings 14 are formed at points along the spacing members 1.

It will be understood that numerous details of the constructions shown may be altered or omitted and still other modifications produced without departing from the spirit of this invention as defined by the following claims.

I claim:

1. A reinforcing system for concrete, comprising a plurality of rods, spacing members supporting said rods in rows, and supporting members supporting said spacing members one upon and above the other.

2. A reinforcing system for concrete, comprising a plurality of rods, spacing members supporting said rods in rows, supporting 85 members supporting said spacing members one upon and above the other, and means for securing said spacing members and said supporting members together.

3. A reinforcing system for concrete, comprising a plurality of rods, spacing members supporting said rods in rows, supporting members supporting said spacing members one upon and above the other, and fastening means for securing said rods to the respective spacing members.

4. A reinforcing system for concrete, comprising a plurality of rods, spacing members supporting said rods in rows, supporting members supporting said spacing members 100 one upon and above the other, and fingers extending upwardly above certain of said spacing members and adapted to be bent around the rods supported thereon.

5. A reinforcing system for concrete, comprising a plurality of rods, spacing members supporting said rods in rows, supporting members supporting said spacing members one upon and above the other, and wires carried by certain of said spacing members 110 adjacent to and adapted to be twisted around the rods supported on said member.

6. A reinforcing system for concrete, comprising a plurality of rods, spacing members in the form of thin metal strips supporting said rods in rows, and supporting members having recesses formed therein whereby said supporting members are adapted to receive said strips and support them one above another.

7. A reinforcing system for concrete, comprising a plurality of rods, spacing members in the form of thin metal strips supporting said rods in rows, and supporting members each comprising a pair of depending legs 125 spaced apart at their lower ends and connected together at their upper ends, said legs having notches extending inwardly from the upper and lower ends thereof whereby the lower parts of said supporting 130

- members straddle one of said strips and have another of said strips resting in the notches in the upper ends thereof so as to support said strips one above another.
- 5 8. A reinforcing system for concrete, comprising a plurality of rods, spacing members in the form of thin metal strips supporting said rods in rows, supporting members each comprising a pair of depending legs spaced apart at their lower ends and connected together at their upper ends, said legs having notches extending inwardly from the upper and lower ends thereof whereby the lower parts of said supporting members straddle one of said strips and have another of said strips resting in the notches in the upper ends thereof so as to support said strips one above another, and coacting shoulders on said strips and said supporting members adapted to have interlocking engagement for securing said strips and supporting members together.
- 10 9. A reinforcing system for concrete, comprising a plurality of rods, spacing members in the form of thin metal strips supporting said rods in rows, supporting members each comprising a pair of depending legs spaced apart at their lower ends and connected together at their upper ends, said legs having notches extending inwardly from the upper and lower ends thereof whereby the lower parts of said supporting members straddle one of said strips and have another of said strips resting in the notches in the upper ends thereof so as to support said strips one above another, and coacting shoulders on said strips and said supporting members adapted to have interlocking engagement for securing said strips and supporting members together.
- 15 10. A reinforcing system for concrete, comprising a flat metal spacing member, supporting members for supporting said spacing member on a mold with the face thereof substantially parallel with one wall of said mold, a row of reinforcing rods supported on said spacing member, other supporting members supported on said spacing member, another flat metal spacing member mounted on edge on said other supporting members, and a row of reinforcing rods supported on said second-mentioned spacing member.
- 20 11. A reinforcing system for concrete, comprising a flat metal spacing member, supporting members for supporting said spacing member on a mold with the face thereof substantially parallel with one wall of said mold, a row of reinforcing rods supported on said spacing member, other supporting members supported on said spacing member, each of said other supporting members being in the form of a pair of depending legs spaced apart at their lower ends and connected together at their upper ends and having lugs on said legs bent to lock said supporting members to said spacing member, said supporting members having notches formed in the upper ends thereof, a flat metal spacing member supported on edge in the notches in said supporting members, and reinforcing rods supported on said second-mentioned spacing member.
- 25 12. A reinforcing system for concrete, comprising a flat spacing strip arranged on edge for supporting reinforcing rods in a row, and members for supporting said strip, each of said members comprising a pair of legs connected together at their upper ends and spaced apart at their lower ends and having a seat formed thereon to receive and support said strip.
- 30 13. A reinforcing system for concrete, comprising a flat spacing strip arranged on edge for supporting reinforcing rods in a row, and members for supporting said strip, each of said members comprising a pair of legs connected together at their upper ends and spaced apart at their lower ends and having a slot extending inwardly from the upper end thereof so as to form a seat adapted to receive and support said strip.
- 35 14. A reinforcing system for concrete, comprising a flat spacing strip arranged on edge for supporting reinforcing rods in a row, and members for supporting said strip, each of said members comprising a pair of legs connected together at one end and spaced apart at the other, and having a seat formed thereon so as to receive and support said strip.

Signed at Chicago this 19th day of Dec. 1917.

HENRY H. LAMPERT.
